(57) **CLAIM**

The ornamental design for a transfer device for medical application as shown and described.

DESCRIPTION

FIG. 1 is an isometric view of a transfer device for medical application showing our new design;
FIG. 2 is another isometric view thereof;
FIG. 3 is a front elevation view thereof;
FIG. 4 is a rear elevation view thereof;
FIG. 5 is an elevation view thereof from the right side;
FIG. 6 is an elevation view thereof from the left side;
FIG. 7 is a top plan view thereof; and,
FIG. 8 is a bottom plan view thereof.
